COMBINED DOOR HANDLE AND MOUNTING PLATE THEREFOR

Fred W. Crew, Detroit, Mich.

Application August 23, 1957, Serial No. 47,487

Term of patent 14 years

(Cl. D10—8)

Fig. 1 is a front elevation of a combined door handle and mounting plate therefor, showing my new design.

Fig. 2 is a side elevation.

Fig. 3 is a back elevation.

Fig. 4 is a plan view.

I claim:

The ornamental design for a combined door handle and mounting plate therefor, substantially as shown.
